ELECTRIC DISCHARGE SYSTEMS

Richard M. Somers, West Orange, N. J., assignor
to Thomas A. Edison, Incorporated, West
Orange, N. J., a corporation of New Jersey

Application April 6, 1940, Serial No. 328,238

8 Claims. (Cl. 176—124)

This invention relates to electric discharge systems, and more particularly to systems wherein a main arc discharge is maintained between appropriate electrodes in a gaseous atmosphere. Throughout the specification the term "gaseous" has been employed to denote either a gas or a vapor or a combination of gases and/or vapors, while the terms "gas" and "vapor" have each been used in a more specific sense.

This application is filed as a continuation in part of my co-pending application, Serial No. 62,583, filed February 6, 1936.

It is an object of my invention to provide generally improved means and methods for starting the main arc discharge.

It is another object to provide starting means and methods adapted to cause the main arc establishment quickly after the supply of current to the system, but with the electrodes in proper condition of emissivity.

It is another object to provide starting means and methods efficiently operative, with supply voltages of 110 volts and less, to start the main arc discharge in devices having material positive columns.

It is another object to provide improved means and methods for quick heating of the electrodes preliminary to the establishment of the arc discharge.

Other objects are the provision of a generally improved discharge system and device, and of improved electrode structures and electrodes therefor.

Still another object is the provision, particularly in a system adapted for alternating current operation, of improved means and methods for equalizing the temperatures of a plurality of main electrodes, especially during the initial heating thereof.

Yet another object is the provision of improved means and methods for synchronizing the arrival of a plurality of main electrodes at normal emissivity.

Other and allied objects will more fully appear from the following description and the appended claims.

In the description reference is had to the accompanying drawing, of which:

Figure 1 is a view of a system incorporating my invention, being a partly elevational and partly vertical sectional view of a typical discharge device together with a schematic diagram of further or circuit portions of the system;

Figure 2 is an enlarged sectional view of one of the electrode structures of the device of Figure 1;

Figure 3 is an end view of the electrode structure shown in Figure 2; and

Figures 4 and 5 are wholly schematic diagrams of the system shown in Figure 1.

Reference being had to Figure 1, there will be seen the discharge device 1a, which may for example be a luminous U-shaped device comprising the elongated glass envelope 2 having the seals 2b and 102b at its respective extremities. The space 2' within the envelope 2 is evacuated of air and filled with a noble gas, such as neon, krypton or argon, or combination of gases. Additionally to the gas filling there may be provided within the space 2' a source of metal vapor, such as the deposit 2" of mercury, adapted to vaporize to an extent depending on the heating of the device; the source 2" may be quantitatively in excess of the amount which can vaporize in the normal operation of the device, in which case the operating vapor pressure will be determined among other things by the cooling facilities of the device, or the source 2" may be quantitatively limited to an amount which will always fully vaporize in normal operation to provide a predetermined vapor pressure. I may mention by way of example that I have employed my invention to great advantage in connection with a device having a quantitatively limited source 2" of mercury vapor adapted to provide an operating vapor pressure of about 10 mm. Hg, and a noble gas filling of argon at a pressure of about 4 mm. Hg.

Passing through the seal 2b are the lead-in wires 4' and 4", and imbedded therein is the additional inwardly extending wire 4"'; and passing through the seal 102b are the lead-in wires 104' and 104", and imbedded therein is the additional inwardly extending wire 104''. On each of these two groups of wires is supported an electrode structure which is desirably of the "furnace" type which I have disclosed and claimed in Patent No. 2,112,718. This structure involves relatively low masses, so that the time period required for its heating is inherently relatively short. Since the two structures, which are identified in Figure 1 as 4a and 104a respectively, are entirely similar, a description of the structure 4a only will be given, it being understood that the structure 104a, may comprise an identical arrangement of identical components (to each of which has been assigned a number 100 higher than to the corresponding component of the structure 4a). The structure 4a appears in detail in the enlarged cross-sectional Figure

The main electrode proper, or 95, is shown by way of non-limitative example as a nickel cup 96 which, while permissibly of solid material, is desirably of fine mesh. This cup is filled with a mixture 97 of alkaline cathode coating material (such as barium and strontium oxides or carbonates) with flake nickel, permissibly in an organic carrier such as amyl acetate; the size of the flakes for example has been of the order of $\frac{1}{8}$ " by $\frac{1}{8}$ " $\times$ .00004". This mixture has been

packed into the cup 96, and the filled cup baked at high temperature in a hydrogen atmosphere to remove the carrier, at least partially to degas the electrode, and to produce alkaline oxides from the carbonates if the latter have been employed. The exterior bottom of the cup 96 may be welded to the nickel or other supporting wire 5b, which in turn is welded to the lead-in wire 4', so as to maintain the open top of the cup facing the center of the device 1a.

Supported about the electrode 95, co-axial therewith and spaced at least slightly therefrom, is an alumina or other ceramic tube 6a, of length preferably exceeding by several times the axial length of the electrode; preferably this will overhang the latter to a greater extent in the direction of the center of the device 1a than in the opposite direction. Surrounding the tube 6a is a nickel or other metallic shielding cylinder 7, of appreciably greater diameter than the tube 6a and preferably of slightly greater length; the cylinder 7 is maintained co-axial with the tube 6a by two mutually similar nickel or other metallic end-members 1a and 1b at the ends respectively toward and away from the center of the device 1a. These end members may be outwardly flanged at their peripheries to fit within the end portions of the cylinder 7, and may be provided with the central holes 1a' and 1b', respectively, inwardly flanged to fit within the end portions of the tube 6a. The hole 1a' serves to pass the arc stream to and from the main electrode 95; the hole 1b', however, is desirably at least substantially closed, wherefore I may provide the disc 31 secured against the outer face of the end member 1b within its peripheral flange. The electrode-supporting wire 5b may pass through the disc 31 within an insulating bushing 31'.

A heater winding 6, preferably of relatively fine wire closely spaced, is provided about the tube 6a, for example for nearly the full length of the tube. Desirably there is coated and dried over the heater winding a solution of alumina powder in amyl acetate, or the like, to form an insulating layer 6b in which the heater winding is imbedded; this reduces the danger of shorting of turns and otherwise renders the heater more sturdy. The extremities of the winding 6 are designated as 32 and 34; the extremity 32 nearer the seal 2b is connected to a refractory wire 33 which passes, through a refractory insulating tube 33', outwardly of the chamber 36 formed between the tube 6a and the cylinder 7, the wire 33 being welded to the lead-in wire 4' and thus electrically connected with the main electrode 95. The other winding extremity 34 is connected to the lead-in wire 4'', which passes into the chamber 36 and longitudinally thereof into adjacency with the extremity 34; the lead-in wire 4'', from seal 2b to substantially its extremity, may be covered by a refractory insulating tube 37. The additional inwardly extending wire 4''' may be welded to the cylinder 7, for further mechanical support of the enclosure 7-1a-1b, which in its entirety is designated as 1'.

The external circuit illustrated in Figure 1 in association with the device 1a comprises the connection of lead-in wires 4' and 104' to the line terminals 9 through ballasting means; these have been illustrated as the serially disposed choke coil 16a and the incandescent lamp 16b, though it will be understood that no limitation as to form of ballast is intended, and that either

choke coil or lamp might be omitted. The lead-in wires 4'' and 104'' are connected together, optionally through an impedance such as resistor 40a. Thus the heater windings, together with 40a when employed, are mutually in series and together in parallel with the main discharge path between main electrodes 95 and 195.

Adjacent the main electrodes 95 and 195 there are employed respective auxiliary electrodes.

10 These are provided with emissive coatings; and they, as well as the main electrodes, are subjected to substantial heating. As the cathode fall of both auxiliary and main electrodes is reducing in response to their heating, a discharge between each auxiliary electrode and the respectively adjacent main electrode is initiated and rapidly increased, quickly forming a strong auxiliary arc discharge. In response to this auxiliary arc discharge the main discharge strikes through the device from one main electrode to the other.

The enclosures 1' and 107' have themselves been employed to form the auxiliary electrodes.

15 Each enclosure, being in very close thermal association with the heater winding for the adjacent main electrode—or, in other words, forming a portion of the electrode heating furnace—is efficiently heated in definite relationship to the heating of that electrode; this relationship will 20 of course be somewhat different for different portions of the enclosure. In general, that portion of the enclosure principally active in performing the auxiliary electrode function will be that portion to which an emissive coating is applied, and I accordingly apply such a coating to that enclosure portion which heats in the most desirable relationship to the main electrode. While my invention is not limited thereto, I have 25 found a preferred relationship to be one wherein the enclosure portion heats somewhat more slowly than the main electrode proper, and is separated from the latter by a reasonably short and direct auxiliary discharge path. I have 30 found generally satisfactory as an enclosure portion to receive the emissive coating the outside surface 41 of the enclosure end-member 1a (and correspondingly the like surface of the end-member in the enclosure 107'); coating of this surface has been illustrated as 41s in Figure 3.

35 As may be seen in the enlarged fractional cross-sectional Figure 2, each of the enclosures 1' and 107'—and thus each auxiliary electrode—is electrically connected to a point on the respective one of the heaters 6 and 106, as by welding 40 to the enclosure of a tap 38 or 138 from the respective heater. Thus each auxiliary discharge path becomes a shunt connected internally of the device around at least a portion of the respective heater, this portion being designated as 45 6s or 106s.

50 In order for the auxiliary discharge to take place across either of the auxiliary discharge paths, there must be available across that path a voltage slightly greater than the sum of the cathode fall (for small currents) and the ionization potential of the gaseous atmosphere in the path. As I ordinarily employ the system, the voltage available across each path is much less than the cathode fall with the electrodes cold; under these circumstances no discharge will take place when voltage is first applied across the system. But the cathode fall of each electrode is rapidly lowered as a result of the progressive heating thereof by the winding 6 or 106, and will 55 60 65 70 75

presently have fallen to some value—predetermined by the applied voltage, ionization potential, etc.—at which there occurs establishment across each auxiliary discharge path of a discharge, of which the current is at first negligible. The heating of the electrodes by the windings of course continues and the cathode falls for the current actually flowing progressively decrease to zero; then the drop across each auxiliary discharge path may be only slightly greater than the gaseous ionization potential.

It will be appreciated that since each auxiliary discharge path has thermally emissive, heated electrodes at each of its extremities, the auxiliary discharge, in spite of alternating current operation, will occur in both auxiliary discharge paths during each one-half cycle. At some instant in the progress of the auxiliary discharge, it will have reached a critical ionizing value, which involves jointly the total of its production of ions and (since the ions it produces are subject to some steady losses) the rate of its production of ions; this critical value is sufficient to have materially cleared away electronic wall charges and otherwise to permit the striking of the main discharge between the main electrodes, and at such instant the main discharge will strike. I prefer so to adjust the parameters that critical ionizing value will be reached by the auxiliary discharge approximately as the main electrodes reach normal operating temperature and hence emissivity. Such adjustment may be performed by regulating the voltage initially dropping across each auxiliary discharge path, which obviously is jointly affected by the resistance value of the resistor 40a relative to that of the heaters 6 and 106, and by the positioning of the taps 38 and 138 relative to the extremities of the respective heaters.

It will be understood that, in view of the use of resistor 40a, it is possible to place the taps 38 and 138 if desired at or near the respective heater extremities 34 and 134, thus either completely or substantially eliminating any unshunted heater portions. Conversely, when substantial unshunted heater portions are employed, it is possible to omit (i. e., by short-circuiting) the resistor 40a. In the usual instance of employment of the circuit of Figure 1, I have preferred so to omit the resistor 40a, in order to avoid the inherent power loss therein; in this instance the schematic circuit of the system becomes essentially that shown in Figure 4. In typical such cases I have placed the taps 38 and 138 at points distant from the respective extremities 32 and 132 by about $\frac{1}{3}$ of the heater length, so that initially there dropped across each shunted heater portion 6s and 106s a voltage of about $\frac{1}{6}$ of the voltage across the device. Assuming the latter to be 100 volts in view of the small drop caused in the ballasting means by heater current, there would appear across each shunted heater portion a voltage of about 17 volts and across each unshunted heater portion a voltage of about 33 volts. When the auxiliary discharge develops and increases, these respective voltages would shift to the order of 10 and 35—the system voltage having dropped in the order of 10 volts due to increased drop in the ballasting means. When the main discharge strikes these respective voltages would shift to the order of 5 and $12\frac{1}{2}$ volts—the system voltage having dropped to some 35 volts due to now high drop in the ballasting means.

The connection of the auxiliary electrodes 7 and 107 into the heater circuit has so far been

considered in connection with influence on auxiliary discharge; there are, however, converse influences on the heater circuit and its electrode-heating functions. During the time interval 5 through which the auxiliary discharge is taking place, this discharge, in view of the reducing cathode fall, is progressively lowering the voltage across the shunted heater portions 6s and 106s, and hence the current therethrough; finally, during the continuance of the main discharge, the voltage across each shunted heater portion is maintained at less than the gaseous ionization potential. If the resistance values in the entire heater circuit are so arranged that initially there 10 drops across each shunted heater portion 6s and 106s a considerably higher voltage than this final one, the abovementioned progressive lowering of heating effect of these portions will be very appreciable. To secure a corresponding thermal effect on the electrodes, however, the unshunted heater portions are preferably maintained small or eliminated (an appropriate value of external resistor 40a being employed). Figure 5 illustrates the schematic circuit of the system in this 15 instance. A reason for the minimization or elimination of the unshunted heater portions in this instance is that, as the current in the shunted heater portions is reducing, the current in the unshunted heater portions would tend 20 progressively to increase and counteract the former in effect on the electrodes. The action discussed in this paragraph—taking place during the progress of the auxiliary discharge—is of course not to be confused with that reduction 25 30 35 which results from sudden great lowering of the voltage across the entire heating circuit upon striking of the main discharge. The action described in this paragraph is therefore most advantageous when, because of small ballast or other special factors, the degree of voltage reduction upon main discharge striking is not high.

Another influence on the heater circuit of connection of the auxiliary electrodes into that circuit is the establishment of a strong tendency to equalization of temperature and emissivity of corresponding electrodes in the two ends of the device. While theoretically equality between such electrodes would always exist as a result of symmetry of arrangement, in practise there frequently tend to be some inequalities which the effect now under discussion greatly minimizes. Thus for example let it be assumed that as a result of discrepant electrode temperatures the auxiliary discharge is occurring with a given drop in a first of the paths, while in the second opposite path the discharge either is occurring with a higher drop or has not yet started; it is then obvious that greater voltage and current appear across and pass through the second heater, speeding up the heating of the electrodes associated therewith. This equalizing tendency will be understood to continue throughout the duration of the auxiliary discharge in both paths; thus the arrival of the two main electrodes at normal high temperature is synchronized, and possibilities are precluded of one main electrode heating extra rapidly and causing the auxiliary discharge to reach critical ionizing value before the other main electrode is properly heated.

While the device and system which I have above disclosed are nicely adapted for operation from alternating current, it will be understood that they may be employed for operation from direct current (choke coil ballast 16a being of course omitted). It is further to be understood

that at least most of the features of special utility remain of value in such direct current operation. Thus for example, although the desirable formation of auxiliary discharges in both ends of the device does not, with any particular connection to direct current, require the efficiently provided emissivity of both auxiliary electrodes, it insures the existence of that emissivity of the appropriate one of those electrodes when the system is connected without regard to polarity. It is also to be understood that certain of the advantages of particular features of my invention will be retained, with either alternating or direct current, even though one of the auxiliary electrodes be omitted and the auxiliary discharge therefore employed in one end only of the device.

It will finally be understood that while I have disclosed my invention in terms of a particular embodiment thereof, I do not thereby intend any unnecessary limitation; rather the scope of my invention, including its several combinations, sub-combinations and elements, is intended to be expressed in the following claims.

I claim:

1. In combination in a gaseous discharge system: two main electrodes forming a main arc discharge path; two thermally emissive auxiliary electrodes respectively adjacent said main electrodes; and two heaters for said auxiliary electrodes respectively, said heaters being serially connected across said discharge path, and each of said auxiliary electrodes being connected to a point on the respective said heater.

2. In combination in a gaseous discharge system: two main electrodes forming a main arc discharge path; two auxiliary electrodes respectively adjacent said main electrodes; two heaters for said auxiliary electrodes respectively; and impedance means serially connected between said heaters, said heaters and impedance means being connected across said discharge path, and each of said auxiliary electrodes being connected to a point on the respective said heater.

3. In combination in a system for main arc discharge between two separated electrode structures: two heater windings respectively included in said structures and connected in series with each other, and means for energizing said serially connected windings to develop across each a voltage sufficient for ionization of said atmosphere, each of said windings having associated therewith, to be heated thereby and in conductive community with respective portions thereof between which appears a voltage sufficient for the establishment of a local arc discharge, mutually adjacent thermally emissive electrodes.

4. In combination in a system for main arc discharge between two separated electrode structures: two heater windings respectively included in said structures, current-controlling means forming a series circuit with said windings, and means for energizing said circuit to develop across each winding a voltage sufficient for ionization of said atmosphere, each of said windings having associated therewith, to be heated thereby and in conductive community with respective portions thereof between which appears a voltage sufficient for the establishment of a local arc discharge, mutually adjacent thermally emissive electrodes.

5. A pair of electrode systems for use in a gaseous atmosphere as respective terminals of a pos-

itive-column main arc discharge path having a heater circuit in shunt thereto, each of said electrode systems comprising, in combination, two portions each comprising material of high thermal emissivity, and a heater winding serially connected in said circuit to receive in the absence of discharge a voltage more than sufficient for ionization of said atmosphere, said portions in each of said systems being heated by the winding in that system and being conductively common with respective parts thereof between which initially appears a voltage more than sufficient for said ionization, whereby in each of said systems a local arc discharge develops between said portions and thereafter regulates the voltage across and current in the winding therebetween.

6. A pair of electrode systems for use in a gaseous atmosphere as the respective terminals of a positive-column main arc discharge path energized by alternating current and having a heater circuit in shunt thereto, each of said electrode systems comprising, in combination, two portions each comprising material of high thermal emissivity, and a heater winding serially connected in said circuit to receive in the absence of discharge a voltage more than sufficient for ionization of said atmosphere, said portions in each of said systems being heated by the winding in that system and being conductively common with respective parts thereof between which initially appears a voltage more than sufficient for said ionization, whereby in each of said systems a local bidirectional arc discharge develops between said portions and thereafter regulates the voltage across and current in the winding therebetween.

7. A pair of electrode systems for use in a gaseous atmosphere as the respective terminals of a positive-column main arc discharge path having a heater circuit in shunt thereto, each of said electrode systems comprising, in combination, two portions each comprising material of high thermal emissivity, and a heater winding serially connected in said circuit to receive in the absence of discharge a voltage substantially more than sufficient for ionization of said atmosphere, said portions in each of said systems being heated by the winding in that system and being conductively common with at least substantially the respective extremities thereof, whereby in each of said systems a local arc discharge develops between said portions and thereafter regulates the voltage across and current in the winding.

8. A pair of electrode systems for use in a gaseous atmosphere as the respective terminals of a positive-column main arc discharge path energized by alternating current and having a heater circuit in shunt thereto, each of said electrode systems comprising, in combination, two portions each comprising material of high thermal emissivity, and a heater winding serially connected in said circuit to receive in the absence of discharge a voltage substantially more than sufficient for ionization of said atmosphere, said portions in each of said systems being heated by the winding in that system and being conductively common with at least substantially the respective extremities thereof, whereby in each of said systems a local bidirectional arc discharge develops between said portions and thereafter regulates the voltage across and current in the winding.

RICHARD M. SOMERS.
